TWO-STAGE CARBURETOR

Elmer Olson, Detroit, Mich., assignor to George
M. Holley and Earl Holley

Application April 27, 1942, Serial No. 440,674

3 Claims. (CL 261—23)

The object of this invention is to improve the operation of two-stage carburetors in which the second stage is brought into action when the velocity of air through the first stage reaches a certain critical value.

In the operation of these two-stage carburetors, certain difficulties have arisen: First, there has been a tendency for the inactive carburetor to cause the active carburetor to lean out, because it is usual to use a common float chamber and a common fuel metering system for the two stages, and the inoperative fuel nozzle bleeds air into the operative one. Secondly, there has been a tendency for the engine to surge with such a fuel system, for the same reason. Thirdly, it is desirable that the operator have some control on the operation of the second stage, that is to say, that the second stage should not become operative until the throttle is almost wide open. For example, it is desirable not to open the second stage under these circumstances: a two-stage carburetor is usually made so that the capacity is greater than a single carburetor would be on the same engine. The low speed metering and operation would not be so good with the increased capacity. The second stage is set so as to open at wide open throttle beyond the critical low suction range. At the same air flow part throttle the second stage would open too soon and destroy the beneficial effects of high velocities, etc.

The moment the throttle is closed, or even partially closed, the automatic means controlling the second stage are therefore prevented from operating. Finally, when the throttle is closed, I utilize the inlet manifold suction to assist in closing the second stage, so as to overcome any friction in the mechanism which might tend to prevent or delay the closure of the second throttle.

In the drawings:

Fig. 1 shows the main features of my invention arranged in one elevation.

Fig. 2 shows a cross-sectional elevation taken on plane 2—2 of Fig. 1.

Fig. 3 shows a cross-sectional elevation taken on plane 3—3 of Fig. 1.

Fig. 4 is a partial section on the plane 2—2 of Fig. 1 when the throttle is partly open showing the position of the controlling valve.

Fig. 5 is a similar section showing the throttle almost wide open, showing the position of the controlling valve.

Fig. 6 shows a plan view looking down.

Fig. 7 shows a cross-sectional elevation taken on plane 7—7 of Fig. 6.

Fig. 8 is a partial elevation on the plane 8—8 of

Fig. 6, showing the accelerating means for the secondary venturi 14.

Fig. 9 is a partial elevation on the plane 9—9 of Fig. 6, showing a corresponding accelerating means for the primary venturi 12.

In Fig. 1, 10 is the air entrance; 12 is the primary venturi of the first stage carburetor, which is in operation at all times; 13 is the primary nozzle that supplies fuel to the venturi 12; 14 is the secondary venturi and is therefore the venturi of the second stage carburetor; 15 is the secondary nozzle discharging fuel therein; 16 is the manually operated throttle shaft; 17 is the throttle for the first stage carburetor mounted thereon; 18 is the automatically operated throttle shaft and 19 is the throttle for the second stage carburetor. 20 is the manually operated throttle lever which is also connected to the fuel pump required for the acceleration of the engine. The lever 20 controls the throttle shaft 16 and the throttle 17, and therefore controls the flow of air through the primary venturi 12 which is in operation at all times. The flow of air through the venturi 12 and a valve 29 (Fig. 2) integral with the throttle shaft 16 jointly controls the opening and closing of the throttle 18. Both carburetors deliver mixture to an exhaust heated inlet manifold 30.

The automatically controlled throttle shaft 18 is controlled by the lever 21 connected through a link 22 with the bell crank lever 23 with the pin 24 connected to the diaphragm 25. The throttle 18 is thus maintained in the closed position by a spring 26. The chamber 27 to the left of the diaphragm 25 is connected through a pipe 28 with the cylindrical valve 29 (see Figs. 2, 4 and 5).

The valve 29 has in it a passage 31 and admits through this passage the inlet manifold suction derived from a passage 32 communicating with the mixture outlet to the chamber 27 adjacent to the diaphragm 25 when the throttle is closed. There is a pipe 28 which connects the chamber 27 with the valve 29.

It will be seen that when the throttle is closed (Fig. 2) and when the throttle is partly open (Fig. 4), the inlet manifold suction is admitted to the chamber 27 so as to be operative upon the left hand side of the diaphragm 25, thereby supplementing the action of the spring 26 and keeping the throttle 18 closed. During this period the pressure on the right hand side of the diaphragm 25 is practically atmospheric.

When the throttle is almost wide open, that is to say, in the position shown in Fig. 5, atmospheric pressure is admitted through an opening

33 and through a passage 34 in the valve 29 to the pipe 28. This atmospheric pressure is admitted to the chamber 27 located on the left hand side of the diaphragm 25. Under these circumstances, the spring 26 is the only force holding the throttle 19 closed. When this condition arises a multiplication (2 to 1) of the suction in the venturi 12 becomes operative. This suction is derived from a small venturi 35 located between the venturi 12 and the venturi 14, which communicates with the throat of the venturi 12 and this increased suction is transmitted through a passage 36 from the throat of the venturi 35 to a chamber 37 located on the right hand side of the diaphragm 25. Assuming that the suction thus created in the throat of the venturi 35 is great enough to overcome the spring 26, the diaphragm 25 is then moved to the right carrying with it the pin 24 which raises the link 22 and the throttle 19 opens.

MAIN FUEL SYSTEM
(Figs. 2, 3, 6 and 7)

The normal fuel supply enters from a float chamber 50 through the drill orifice 38 into a well 39 in which there dips a low speed tube 40 which communicates with an inclined low speed passage 41 in the bridge 42 which supports the nozzle 13. This passage communicates with a corresponding inclined passage 11 in the right leg of the bridge which communicates with a vertical passage 43, which discharges through openings 44 and 45 located adjacent to and on opposite sides of the upstream lip of the throttle 17 when the throttle 17 is in its closed position, this being the usual method of supplying the low speed fuel. The main fuel flows out of the well 39 through a passage 46 to the main nozzle 13 where it receives air through a plug 47, which plug also communicates through a small passage 48 at the point in the low speed fuel passage 41—11 at the place where it makes a 90° turn. All these are known elements of a well known carburetor.

When the engine is in operation it happens that when the throttle is wide open and the engine is under a heavy load, means must be provided to give a little extra fuel. The means disclosed in U. S. Patents 1,575,877 and 2,035,636 is the preferred means for securing this result. This means includes a valve 49 (Fig. 7) which is located within the float chamber 50 and is held open by a spring 55 and permits fuel to flow through an opening 51 to a chamber 52. This chamber 52 is separated from an air chamber 53 by means of a diaphragm 54, which, when subjected to suction in the chamber 53, moves the valve 49 against the spring 55. The chamber 53 communicates through the passage 56 with the mixture outlet on the engine side of the two throttles (Fig. 3). Fuel flows through openings in the walls of the chamber 52 to a restricted opening 57 and a larger opening 59 controlled by a non-return valve 60 retained by a pin 61.

Whenever the throttle 17 is closed with the engine running, a large suction is applied to the lower side of the diaphragm 54 and, the float chamber being at atmospheric pressure, the valve 49 is closed and these restrictions 57 and 59 are then inoperative. The check valve 60 prevents air being drawn down into the well 58 into the chamber 39.

When there is a heavy load, the suction in chamber 53 transmitted through the passage 56 disappears, and hence the valve 49 opens, fuel is admitted through the restriction 57 to the well

39, supplementing the fuel which the well 39 receives through the plug 38. At the same time, fuel is admitted to a well 58 through the restriction 59, which passage is somewhat larger than the restriction 57. The check valve 60 normally closes the passage 59 and prevents fuel flowing from the well 58 to the well 39 which I have discovered disturbs the fuel metering characteristics of the nozzle system 46, 39, 38, of the primary carburetor 12, 13, 17, even when air is not drawn down the well 58. A surge of fuel between the two wells 39 and 58 takes place in the absence of the check valve 60.

When the throttle 19 is opened, suction is created in the small nozzle 15 which is supported by the bridge 62 and causes suction in the inclined passage 63 which transmits suction to the well 58. The ball 60 is raised off its seat and fuel enters 58 flowing up passage 63, and is discharged through the venturi 15 into the throat 14. A small air bleed 64 admits air to the fuel discharged through 14.

It is also desirable to modify the accelerating means to avoid discharging fuel through the venturi 14 when the throttle 17 is opened at a relatively slow rate when it is desired that the throttle 19 remains closed. Fig. 8 shows the accelerating means for the venturi 12 of the primary carburetor in which the throttle 20 is shown connected to a link 65 which carries a pin 66 connected to an L-shaped element 67 which engages with a solid link 68 and compresses a spring 69 which propels the piston 70 downwardly into the chamber 71. Fuel is admitted from a float chamber 50, past the check valve 51 on the up-stroke of the piston 70, that is to say, when the throttle lever 20 is moved to close the throttle 17. On opening the throttle 17, by moving the manually controlled throttle lever 20, the spring 69 is compressed, the piston 70 gradually descends and fuel passes through a passage 72, past a check valve 73, into one leg of a V-shaped element 74. The fuel passes out of the small opening 76 directed 45 against the fuel nozzle 13 (Fig. 9).

In Fig. 8 a section is shown through the other leg of the V 74 and the fuel then emerges through the outlet 75, which directs the flow of fuel against the fuel nozzle 15 in the venturi 14. However, in this case, a check valve 77 supported by a spring 78, prevents the discharge of fuel through the opening 75 except when the throttle lever 20 is moved rapidly enough so that the pressure built up in the cylinder 71 is great enough to open the check valve 77, in which case the engine will normally accelerate fast enough so that by the time any fuel has a chance to accumulate on the closed throttle 19, the diaphragm 25 will be moving to the right, the throttle 19 will be opening so that there will be no inconvenience due to the sudden discharge of fuel into the mixture outlet.

The link 65 is connected to the throttle lever 20 by means of the pin 79 and alternative openings are sometimes provided in which the pin 79 can be inserted and the stroke of the piston 70 varied.

In normal (economical) operation of the carburetor no fuel at all is discharged through the opening 75, the throttle 17 being opened slowly enough so that the check valve 77 is never unseated.

What I claim is:

1. In a carburetor having a primary stage and a secondary stage, each having a Venturi mixing

chamber, a fuel nozzle in each venturi, a mixture outlet for each mixing chamber, a throttle in each mixture outlet, each controlling the flow through one of said venturis, manual means for opening and closing the throttle of the first stage, automatically controlled means for opening and closing the throttle of the second stage, said automatic means comprising a chamber, a moving wall therein dividing said chamber into two parts, a passage connecting one part with the suction in the throat of the venturi of the first stage so as to reduce the volume of said part by the moving of said wall, yieldable means opposing said movement, a valve controlled by said manual throttle, a suction passage connecting said valve with the other part of the chamber, a passage in said valve, a valve seat, a part therein, said port communicating with the mixture outlet on the engine side of the throttle, the passage in said valve being adapted to place the mixture outlet in communication with said suction passage to supplement said yieldable means in opposing said movement of said wall, a second port in said valve seat, said port and valve being adapted to admit atmospheric pressure through said suction passage to said chamber when said manually operated throttle approaches the wide open position, said atmospheric pressure cooperating with the suction in the throat of the first stage venturi, linkage connecting said moving wall with said throttle of said second stage whereby the secondary throttle is held shut by the suction in the mixture outlet, when

the manually controlled throttle is shut and is automatically opened by the suction in the venturi of the first stage when the manually operated throttle approaches the wide open position and when the engine runs above the speed required to create a predetermined suction in the venturi of the primary stage.

2. A device as set forth in claim 1 in which there is a fuel supply chamber common to both fuel nozzles, a continuously open passage communicating fuel to the nozzle supplying the primary venturi of the first stage, a second fuel passage controlled by a valve responsive to mixture outlet suction adapted to supply fuel to said nozzle when the mixture outlet suction falls below a predetermined value, a passage connecting said second fuel passage to the nozzle in said second venturi, and a check valve in said passage for the purpose described.

3. A device as set forth in claim 1 in which there is an accelerating fuel pump responsive to the operation of the manually controlled throttle, two fuel outlets from said accelerating device, one outlet being adapted to discharge fuel into the primary venturi, the other outlet being adapted to discharge fuel into the secondary venturi, said second fuel outlet having a spring-loaded check valve therein, the first fuel outlet being open at all times whereby fuel is discharged only into the first stage when the engine is accelerated at a reasonable rate.

ELMER OLSON.
